UNITED STATES PATENT OFFICE

2,466,203

ATTACHMENT FOR GUN BARRELS

Earl Bristow, Harrisburg, Ill., assignor of one-half
to E. L. Ghent, Harrisburg, Ill.

Application August 25, 1947, Serial No. 770,351

4 Claims. (Cl. 42—79)

1

The present invention relates to attachments for gun barrels and it consists in the combinations, constructions and arrangements of parts herein described and claimed.

It is an object of the invention to provide an attachment for gun barrels which is simple and inexpensive in construction, easy to operate and yet efficient and effective in its use.

Another object of the invention is the provision in a device of this character of means whereby a choke may be remotely operated without the necessity of removing a gun from the shoulder of the user.

A further object of the invention is the provision of a novel means and mechanism for varying the size of the pattern of shot emanating from a gun.

A further object of the invention is the provision of semi-automatic means for re-setting a device of the character set forth to normal, that is to say, inoperative position upon the firing of each round.

Other and further objects of the invention will become apparent from a reading of the following specification taken in conjunction with the drawings, in which:

Figure 1 is a side elevational view of an embodiment of the invention mounted upon a shotgun.

Figure 2 is an enlarged fragmentary bottom plan view of the device looking in the direction of the arrows 2—2 in Figures 1 and 3.

Figure 3 is a side elevational view of Figure 2.

Figure 4 is an enlarged sectional view taken along line 4—4 of Figure 3.

Figure 5 is a sectional view taken along line 5—5 of Figure 4.

Figure 6 is a sectional view taken along line 6—6 of Figure 4.

Figure 7 is an enlarged sectional view taken along line 7—7 of Figure 2, and

Figures 8 and 9 are perspective views of elements of the invention.

Referring more particularly to the drawings, there is shown therein a shotgun 10 having a conventional stock 11, trigger 12 and barrel 13.

Adjacent the outer end of the barrel 13 there is threaded a retaining collar 14 by means of inwardly extending threaded portions 15. A series of fingers 16, each of which is arcuate in transverse cross section and each of which is provided with side recesses 17 adjacent its rear end, are adapted to be held upon the barrel by means of a retaining collar, which fits snugly about the fingers and has its threaded bosses 15

passing through openings formed by registering recesses 17 of the fingers.

The fingers are relatively thin at the rear thereof and become increasingly thicker toward their front ends.

Surmounting the fingers 16 between the forward ends thereof and the retaining collar 14 is a slidably mounted actuating ring 18 into the lower rear side of which is threaded, as indicated at 19, a rearwardly extending rod 20 which terminates in an integrally formed finger grip 21.

A clamp member 22 is mounted on the barrel 13 adjacent the finger grip 21. The rod 20 is adapted to pass through an opening 23 in the lower portion of the collar 14 and an opening 24 in the lower portion of the clamp member 22.

A tension spring 25 is fastened in an opening in the rod 20, as indicated at 26, and has its other end fastened in an opening in the clamp member 22, as shown at 27.

A front sight 28 is affixed in the upper side of the retaining collar 14 and a housing 29 for the rod 20 and spring 25 is fastened to the underside of the retaining collar by screws 30 or the like and by a latch member 31 carried by the clamping member 22.

The operation of the device is quite simple. If it is desired to use full bore, the finger grip 21 is pulled rearwardly thus causing the actuating collar 18 to move rearwardly and thereby allowing resiliency of the fingers 16 to cause them to be spread and spaced from each other at their forward ends.

When a closer pattern of shot is desired, the finger grip 21 is moved forwardly causing the rod 20 and consequently the actuating collar 18 to move forwardly thus bringing the fingers closer together due to their increasing thickness in a forward direction. The bore is now restricted and thus restriction may be controlled by moving the actuating collar to whatever position desired. Frictional grip of the fingers with the ring holds the ring in a set position.

When the device is set for other than full bore and the gun is fired, the force of the charge passing through the fingers will tend to spread them, and as the fingers are spread they exert a cam action upon the ring and shift the ring rearwardly so that the spreading of the fingers is not prevented.

The spring 25 exerts pull upon the rod 20 and urges it rearwardly so that the ring will be easily moved back along the fingers to its retracted position against the retaining collar 14, that is to say, in a full bore position.

While but one form of the invention has been

shown and described herein, it will be readily apparent to those skilled in the art that many minor modifications may be made without departing from the spirit of the invention or the scope of the appended claims.

What is claimed is:

1. A device of the character described comprising a retaining collar adapted to be threaded adjacent the outer end of a gun barrel, a plurality of fingers arcuate in cross section and, when assembled together forming a choke having a circular cross section and flaring towards its front end, said collar gripping rear portions of the fingers and having members passing through said fingers for preventing longitudinal movement of the fingers upon the barrel and an actuating ring slidably mounted upon said fingers and adapted to gradually move the outer ends of said fingers toward each other as the ring is shifted forwardly along the fingers.
2. A device of the character described comprising a retaining collar of a diameter adapting it to be threaded upon the outer end portion of a gun barrel, a plurality of fingers arcuate in cross section and, when assembled together forming a choke having a circular cross section, said collar fitting tightly about rear portions of the fingers and having portions passing through openings in the fingers for retaining the fingers upon the barrel and having threaded engagement with the barrel, an actuating ring slidably mounted upon said fingers and serving to gradually move the outer ends of said fingers toward each other as the ring is shifted forwardly along the fingers.
3. A device of the character described comprising a retaining collar adapted to be threaded adjacent the outer end of a gun barrel, a plurality of forwardly flaring fingers arcuate in cross section and, when assembled together forming a choke having a circular cross section, means for retaining said fingers upon the barrel by said retaining collar, an actuating ring fitting about the choke and slidably mounted upon said fingers and adapted to gradually move the outer ends 45

of said fingers toward each other as the ring is slid forwardly along the fingers, a rearwardly extending rod affixed to said actuating ring and having a grip formed at the rear end thereof, and a spring arranged to assist movement of said rod and the actuating ring in a rearward direction when the fingers are spread by a charge and exert a cam action upon the ring and urge the ring rearwardly when the gun is fired.

4. A device of the character described comprising a retaining collar adapted to be threaded adjacent the outer end of a gun barrel, a plurality of fingers arcuate in cross section and, when assembled together forming a choke having a circular cross section, means for retaining said fingers upon the barrel by said retaining collar, an actuating ring fitting about the choke and slidably along said fingers and serving to gradually move the outer ends of said fingers toward each other as the ring is slid forwardly along the fingers, a rearwardly extending rod affixed to said actuating ring, a grip formed at the rear end of said rod, a spring arranged to urge said rod and actuating ring in a rearward direction and assist rearward movement of the ring when the fingers are flared by a charge of a passing shot and exerts a cam action upon the ring to force the ring rearwardly when the gun is fired, and a casing enclosing said rod and spring.

EARL BRISTOW.
